UNITED STATES PATENT OFFICE.

CATHERINE SHIELS, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 14,822, dated February 26, 1884.

Application filed January 23, 1884. Term of patent 3½ years.

To all whom it may concern:

Be it known that I, CATHERINE SHIELS, of the city, county, and State of New York, have invented and produced a new and original Design for a Pattern of a Girl's Costume, (numbered 9,055;) and I do hereby declare that the engraved prints accompanying this specification convey to any one accustomed to using paper patterns a clear understanding of how a garment made up by the pattern will appear.

The design shows a princess-front displaying a full plastron Shirred at the neck and waist-line, and separated and extended below the lower shirrings in the form of round panniers, that exhibit draping-plaits in their back edges, and a half-fitted polonaise-back falling

over a back-skirt section, showing buttons to a little below the waist-line, and exhibiting under-folded plaits at the lower ends of the closing and side back seams, draping-plaits in its front edges, and loopings at the center, coat-sleeves and a standing collar being added.

What I claim as my invention, and desire to secure by Letters Patent, is—

The design for a girl's costume, as shown in the engraved prints accompanying this specification.

CATHERINE SHIELS.

Witnesses:

MARCELLUS CARLETON SHATTUCK,
ALFRED FRANCIS.
